(Cl. D83—1)

To all whom it may concern:

Be it known that I, Albert J. Bruneau, a citizen of the Dominion of Canada, residing at Montreal, in the Province of Quebec, Dominion of Canada, have invented a new, original, and ornamental Design for a Perfume Atomizer, of which the following is a specification, reference being had to the accompanying drawing, forming part thereof.

Fig. 1 is a front perspective view of a perfume atomizer embodying my new design; and

Fig. 2 is a front elevational view thereof.

The other side and rear, not shown, are substantially the same.

I claim:

The ornamental design for a perfume atomizer, as shown and described.

A. J. BRUNEAU.
